UNITED STATES PATENT OFFICE.

JAMES A. TURNER AND EDWARD F. O'SULLIVAN, OF TOLEDO, OHIO.

EMBALMING AND COOLING BOARD.

SPECIFICATION forming part of Letters Patent No. 702,511, dated June 17, 1902.

Application filed July 8, 1901. Serial No. 67,410. (No model.)

To all whom it may concern:

Be it known that we, JAMES A. TURNER and EDWARD F. O'SULLIVAN, citizens of the United States, residing at Toledo, in the 5 county of Lucas and State of Ohio, have invented certain new and useful Improvements in Embalming and Cooling Boards; and we do hereby declare the following to be a full, clear, and exact description of the invention, 10 such as will enable others skilled in the art to which it appertains to make and use the same.

Our invention has reference to an embalming and cooling board, and has for its object to provide an apparatus of this character 15 which may be easily and quickly adjusted to meet the varying lengths of corpses and which may be folded up to occupy a minimum of space, making the same conveniently portable. We have succeeded in reducing 20 the dimensions of our board to such an extent that the same may be carried upon a public thoroughfare or in a public conveyance without attracting undue attention, having the appearance when folded of an ordinary sample-case.

In carrying out our invention we employ the parts and arrangement hereinafter shown, described, and claimed.

In the drawings, Figure 1 discloses our invention as it appears when folded for transportation. Fig. 2 is an elevation showing the board arranged to receive the body of a child, the adjustable section on the right being retracted, whereas the adjustable section on 35 the left is elevated at an angle to the main section of the board to provide a head-rest. Fig. 3 is a transverse section through one of the main sections of the board, the end of the adjustable section being shown in full lines. Fig. 4 shows the inner end of one of the adjustable sections. Fig. 5 shows one of the adjustable sections extended to the full limit of its adjustment. Fig. 6 shows one of the adjustable sections elevated at an angle to the 40 main section of the board to form a head-rest, the same being supported in raised position. Fig. 7 is a section through the board when folded. The legs and the bracket for supporting the head-rest are shown in folded position. Fig. 8 is a view of one of the canopy supports.

Referring to the parts, the board comprises

two main sections 1 and 2 of equal length hinged together at 3, forming a case, as shown in Fig. 1, for the reception of a canopy-cover, 55 embalming instruments, rubber gloves, &c. The case is provided upon the end of one of the main sections with a handle 4 for the purpose of conveniently carrying the same. The case may also be provided with a suitable fastening or lock to secure the main sections when closed. To the outer ends of the main sections 1 and 2 are hinged or otherwise pivotally secured legs 5, which are maintained in unfolded position to support the board by 60 pivoted and slotted bracket-irons 6. The bed of the main sections, upon which the corpse rests, comprises a plurality of slats 7, rigidly secured in position, having spaces between them to receive a plurality of slats 8, forming the adjustable sections 9. The inner ends of the slats 8 are secured to a cross-piece 10, having pivotal projecting ends 11, adapted to be guided in grooves 12 in the side pieces 13 of the main sections. The lower sides of 75 the slats 8 rest upon a cross-piece 14, secured crosswise between the side pieces 13 at their outer ends. As each main section is provided with an adjustable section, the board may be extended at both ends of the same. 80 The normal length of the board when the sections are retracted is forty-two inches, each main section being twenty-one inches in length, and the length of the same when the adjustable sections are extended is six feet 85 five inches.

In Fig. 6 is shown a novel bracket for supporting one of the adjustable sections at a suitable angle to the main section of the board to provide a head-rest. The same comprises a U-shaped metal strap 15, the ends of which are pivoted to the legs on either side of the board. Pivots connected to the U-shaped metal strap 15 at 16 is a second U-shaped member 17, the free ends 18 of which are provided with a plurality of teeth 19, adapted to engage a metal rod or plate 20, secured upon the lower sides of the straps 7 at their outer ends.

21 is a canopy-support employed in connection with our embalming and cooling board.

At the corners of the adjustable sections of our board are provided vertical grooves 22, and in the same are drilled holes 23. The can-

opy-supports are in the form of metal rods bent, as shown, to provide standards 24, the ends 25 being bent inwardly at a right angle to enter the holes 23. When the canopy-supports are in raised position, as shown in Fig. 2, the resiliency of the metal rods forming the same will maintain them in position in the grooves 22. When the board is to be transported, the canopy-supports are removed 10 by spreading the ends of the same apart.

From the foregoing it is evident that we provide an embalming and cooling board which is perfectly adjustable and that we also provide a board which is capable of being folded in a minimum of space, the actual dimensions of the case formed by the board when folded being twenty-one by twenty-two by five inches. The utility, novelty, and simplicity of construction of our invention will 15 be apparent.

Having described our invention, what we claim, and desire to secure by Letters Patent of the United States, is—

In an embalming and cooling board, the 25 slatted main sections 1 and 2, hinged together at 3, the same being provided with suitable leg-supports, the grooved side pieces 13 of the

main sections, the cross-pieces 14, secured crosswise between the outer ends of the side pieces 13, the slatted adjustable sections, slidably mounted with relation to the slatted main sections, having cross-pieces 10 at their inner ends provided with pivotal ends 11 adapted to occupy the grooves in the side pieces 13, and the means for supporting the 30 adjustable section 9 at an inclination to the main section comprising a U-shaped member pivoted to a stationary part of the main section, a second U-shaped member pivoted to the outer end of the first-named U-shaped 40 member, an engaging rod or plate secured to the main section, and teeth provided at the free ends of the second-named U-shaped member adapted to engage the rod or plate upon the main section, substantially as shown 45 and described.

In testimony whereof we hereunto affix our signatures in presence of two witnesses.

JAMES A. TURNEY.
EDWARD F. O'SULLIVAN.
